INVENTOR.
George R. Schlegel.
BY William J. Jackson
ATTORNEY.

UNITED STATES PATENT OFFICE.

GEORGE R. SCHLEGEL, OF NEW BERLINVILLE, PENNSYLVANIA.

MILK-BOTTLE HOLDER.

1,353,498.

Specification of Letters Patent. Patented Sept. 21, 1920.

Application filed February 17, 1920. Serial No. 359,335.

To all whom it may concern:

Be it known that I, GEORGE R. SCHLEGEL, a citizen of the United States, residing at New Berlinville, in the county of Berks and 5 State of Pennsylvania, have invented certain new and useful Improvements in Milk-Bottle Holders, of which the following is a specification.

The principal object of the present invention 10 is to provide a holder designed to prevent the removal therefrom of bottles except by the owner of the holder. A further object is to provide a holder which may be attached to the exterior of a building for 15 the reception of a milk bottle and which holder is provided with releasing mechanism operable only from the interior of the building. A further object is to provide a holder the parts of which may be adjusted 20 to retain either a quart, pint or smaller bottle. Other and further objects will herein-after appear.

The invention consists of the improvements hereinafter described and finally 25 claimed.

The nature, characteristic features and scope of the invention will be more fully understood from the following description taken in connection with the accompanying 30 drawings forming part hereof, and in which:—

Figure 1, is a view in front elevation of a holder embodying features of the invention.

Fig. 2, is a view in side elevation thereof, and

Fig. 3, is a fragmentary view, partly sectioned illustrating details of construction.

For the purpose of illustrating my invention 10 I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of the instrumentalities as herein shown and described.

In the drawings 10 designates a plate of any suitable material the upper part of which carries a casing 11 provided with an overhanging portion 12 shaped and proportioned to accommodate the neck of a milk bottle. Fixed to the lower portion of the

plate 10 are a plurality of brackets 13, spaced apart, one above the other and apertured as at 14. Adapted for detachable connection with respect to said brackets is a 60 basket-like receptacle 15 shaped to accommodate a milk bottle and provided with hooks 16 for engaging with the apertured portions of said brackets. If a quart bottle is to be retained in the holder the receptacle 65 15 is fitted to the lowermost bracket. If a pint bottle is to be retained the receptacle is fitted to the bracket above the lowermost bracket. In practice the plate 10 is secured to a door, partition or other structure 10' 70 so that the holder is upon the exterior side thereof. A description will now be given of the means for locking a bottle with respect to the holder. Within the casing 11 is pivoted a bell-crank lever 17 pivoted to 75 one arm of which is a vertically disposed detent 18 which projects into a barrel 19 and is maintained in this position by reason of the fact that the other arm of the lever is under spring tension as at 20. Also 80 connected with the last mentioned arm is a push-rod 21 which projects through the structure 10' so said rod may be moved outward from the interior of said structure to move the lever 17 around its pivot so as to 85 withdraw the detent from the barrel 19. Adapted for removable insertion within said barrel is a pin 22 having a finger piece 23 at its outer end and a head 24 at its other end adapted to coöperatively engage with the 90 detent 18. The pin has connected thereto a short section of chain 25 wire or equivalent material for engaging around the neck of the bottle. The chain 25, as shown, is attached as at 26 to the interior of casing 11. 95 When a bottle is placed in the receptacle 15 the top of the bottle fits snugly under the overhanging portion 12 of the casing 11 so that when the pin 22 is inserted within the barrel 19 and engages with the detent 100 the chain is drawn taut around the bottle neck thus securely interlocking the bottle with respect to the holder and can only be removed from the holder when a person from within the structure to which the 105 holder is secured manipulates the push-pin. In order to cause the ready ejection of the push-pin from its barrel a cushioned button 27 is positioned in alignment with the head of the push-pin and with which button the 110 said pin has abutting relation in its interlocked position.

It will now be apparent that I have devised a novel and useful construction which embodies the features of advantage enumerated as desirable in the statement of the invention and the above description and while I have in the present instance shown and described the preferred embodiment thereof which has been found in practice to give satisfactory and reliable results, it is to be understood that the same is susceptible of modification in various particulars without departing from the spirit or scope of the invention or sacrificing any of its advantages.

15 What I claim is:—

In a device of the character stated a supporting structure mounted upon the exterior of the building, means for supporting a bottle carried by said structure, a horizontally disposed open-ended barrel located within said casing, said barrel having a ver-

tical slot in the wall thereof, a cushioned button carried by said casing and disposed in alinement with said barrel, a notched bolt normally engaging with said button, a detent extended through said slot and normally engaging the notch of said bolt, a push-rod extended into the building interior, a bell-crank lever connecting said detent and push rod, means carried by said casing to receive the rim of a bottle and flexible means for engaging around a bottle neck said means being fixed at one end to said casing in a plane below the rim receiving means and adapted for detachable connection at its other end with said bolt whereby upon withdrawal of said detent said cushioned button serves to eject said bolt.

20 In testimony whereof, I have hereunto signed my name.

GEORGE R. SCHLEGEL.
